UNITED STATES PATENT OFFICE.

JOSEPH L. MATTHEWS, OF HIGHLAND PARK, NEW JERSEY, ASSIGNOR TO INTERNATIONAL MOTOR COMPANY, OF NEW YORK, N. Y., A CORPORATION OF DELAWARE.

LATHE ATTACHMENT FOR TURNING IRREGULAR PROFILES.

Application filed December 7, 1926. Serial No. 153,065.

The present invention relates to attachments for lathes to be used in turning irregular profiles.

In many instances, shafts of this type are turned instead of being drop forged and the former method often involves removing a considerable amount of material. In existing methods, the removal of this material has required a relatively long time, due to the limited depth of cut which can be taken by a given tool.

An object of the present invention is the provision of an attachment for a lathe which is adapted to hold a plurality of tools and feed them into the work simultaneously in order to divide the cut of a single tool into a plurality of smaller cuts. The features of this design include a means for operating the tools simultaneously in radial directions with respect to the work and in this manner the shaft is made symmetrical with respect to its own axis.

A further object is to provide a means for steadyng the work so that irregularities in the profile may be eliminated as far as possible.

Reference will now be had to the accompanying drawings forming a part hereof for a more detailed description of the invention, 30 wherein:

Figure 1 is an elevation of the lathe attachment showing the cutting tools and showing the pattern and guide means partly in section.

Figure 2 is a section on line 2—2 of Figure 1 and looking in the direction of the arrows.

Figure 3 is a rear elevation of the attachment showing the means for steadyng the work.

Figure 4 is an elevation showing the side of the lathe and the pattern for positioning the tools and steadyng means properly.

Figure 5 is a plan view showing the connection between the pattern track and the tool, or steadyng mechanism.

In the drawings, *a* represents the attachment which is provided with a base portion *a'* which is adapted to slide upon the bed of the lathe and be moved along the lathe by means of a lead screw *a²* and a nut *a³*.

The attachment consists of a body portion *a⁴* provided with circumferential end flanges *a⁵*, to which are bolted, end plates *a⁶*. Upon the outer side of one of these end plates are pivotally secured tool housings *a⁷* by means

of semi-circular shouldered plates *a⁸*. Plates *a⁸* are bolted to the face plates at *a⁹* and have shouldered portions *a¹⁰*. The tool housings are pivoted to the face plate by pins *a¹¹* which are secured by screws *a¹²* and shoulders *a¹³* prevent the housings from being removed by their engagement with shoulders *a¹⁰* of the semi-circular plates. In order to secure a cutting tool, slots *a¹⁴* are provided in the housings, into which tools *a¹⁵* may be adjusted by set screws *a¹⁶*.

At each end of the body portion *a⁴* an annular recess *b* is formed and adapted to receive an annular disc *b'*.

Disc *b'* is provided with three slots *b²* 70 spaced equidistantly about the disc and receive rollers *b³* which are carried by the tool housings and suitably secured thereto. The end plates *a⁶* are provided with slots *a¹⁷* 75 which permit a limited pivotal movement of the tool housing.

It will be seen that the tool housings are pivoted eccentrically with respect to the annular disc so that when the latter is moved within the recess the former will be moved 80 pivotally and the rollers *b³* will ride within the slots *b*. This relative movement will cause the cutting tool to be advanced into or withdrawn from the work, which is designated by the reference character *c*.

In order to steady the work and cause a more accurate cut, means is provided for steadyng the work adjacent the cutting tools and comprises housings *d* similar to the tool housings and operated in the same manner. 90 Instead, however, of being provided with slots to receive the cutting tools, housings *d* are provided with extensions *d'* which have heads *d²* to receive pins *d³*, at the inner ends of which are rollers *d⁴* which bear upon the work *c*. Set screws *d⁵* provide a means for adjusting the pins initially and are mounted in cover plates *d⁶* upon the heads. It will be seen that the movement of the housings *d*, conforms to the movement of the annular 95 ring which is moved in a manner to be described later.

In order to move the annular discs in accordance with a pattern to produce a predetermined profile, the following means is provided.

Brackets *e* are secured to the side of the attachment and have formed therein vertical dovetailed grooves *e'* which receive the dovetails *e²* formed on movable heads *e³*. These 110

heads are, in turn, provided with dove tailed grooves e^4 which receive the dove tails f of secondary heads f' . Vertical screws e^5 in the heads e^3 engage corresponding threads f^2 in the secondary heads so the latter will be moved vertically in the dovetailed grooves e^4 when the screws are turned. The secondary heads f' have formed therein longitudinal grooves f^3 in which blocks g are adapted to slide.

Upon blocks g are pivotally mounted arms h which are secured to the respective rings b' at each end of the body portion a^4 . When the heads e^3 move vertically the blocks g slide in the grooves f^3 to accommodate the relative movement of the arms h and blocks g . Due to this relative movement, the rings will be turned and the tools and steadyng rollers will be moved accordingly. An opening a^{18} is formed in the side of the body portion a^4 to receive the arms h and permit their movement.

The outer faces of the heads e^3 have secured thereto rollers e^6 which ride in tracks i formed in a pattern plate z secured to the lathe. In order to retard the movement of the rollers so that they will be moved to conform with the profile cut by the cutting tools, the track in which the roller e^6 moves, which operates the annular disc of the steadyng rollers, must be formed so that its irregularities are spaced from those operating the cutting tools by a distance equal to that between the cutting tool and the rollers. This is represented diagrammatically in Figure 4.

In order to adjust the positions of the tool housings and roller housings initially, sleeves j are formed on the brackets e and receive shafts j' which are provided with hand wheels j^2 . Formed at the other ends of these shafts are pinions j^3 engaging gears j^4 formed on the upper ends of the screws e^5 .

A cylindrical sleeve k is placed in the body portion of the attachment to prevent foreign matter from falling therein and provide a central portion to permit the work to pass therethrough.

The operation of the device will be evident from the above description. The work c is mounted between the tail spindle c' and head stock c^2 and passes through the attachment a . The lead screw a^2 turns with the work and advances the attachment along the lathe. The advancing of the attachment causes the rollers e^6 moving in the pattern tracks i to move the tools simultaneously into, or away from, the work to produce a desired profile. The cut is divided equally between the three tools and enables a piece to be turned out with far greater speed than heretofore and with a much greater saving of the cutting tool.

While a specific form of the invention has been described herein, it is obvious that the

device may be modified or changed in design without departing from the scope of the invention as set forth in the appended claims.

What I claim is:

1. In an attachment for lathes, a body mounted to move upon the lathe, means to move the body, an end plate carried by the body, tool housings mounted pivotally upon the plate, an annular disc carried by the attachment upon the side of the end plate opposite to the housings, slots in the disc, means carried by the housings to engage the slots, openings in the end plate to receive the engaging means, pattern means, and means to move the disc by the pattern in the movement of the attachment over the lathe.

2. In an attachment for lathes, a body mounted to move upon the lathe, means to move the body, an end plate carried by the body, tool housings mounted pivotally upon the plate, an annular recess in the side of the face plate opposite to the housings, an annular disc carried in the recess, slots in the disc, pins carried by the housings and engaging the slots, openings in the end plates to permit movement of the pins, pattern means, and means to operate the disc by the pattern in the movement of the attachment over the lathe.

3. In an attachment for lathes, a body portion mounted to move upon the lathe, an end plate carried by the body portion, tool housings, means to mount the housings pivotally upon the outer side of the end plate, a semi-circular flange on the housings, semi-circular shouldered plates secured to the face plate and engaging the flanges of the housings, openings in the face plate, an annular recess in the inner face of the face plate, an annular disc carried in the recess, slots in the disc, pins carried by the housings and extending through the openings to engage the slots, a pattern track, an arm secured to the disc, and means for connecting the arm to the track to cause the housings to move simultaneously as the attachment moves along the lathe.

4. In an attachment for lathes, a body portion mounted to move upon the lathe, end plates carried by the body portion, housings carried by each of the end plates, means to mount the housings pivotally thereon, means to mount cutting tools in the housings of one end plate, means to mount steadyng means upon the housings of the other end plate, means to move the housings of each end plate simultaneously, and means to automatically operate the moving means of the steadyng means in accordance with the movement of the cutting tools.

5. In an attachment for lathes, a body portion mounted to move upon the lathe, end plates carried by the body portion, housings carried by each of the end plates, means to mount the housings pivotally thereon, means

- to mount cutting tools in the housings of one end plate, means to mount steadyng means upon the housings of the other end plate, annular recesses in the rear faces of the end plates, annular discs carried in the recesses, slots in the discs, openings in the end plates, pins mounted on the housings and extending through the openings and engaging the slots, a pattern track, a second pattern track similar to the first but having the configuration thereof lagging behind the corresponding configurations of the first track, means to move the ring associated with the tool housings by the first track, and means to move the second ring by the second track, whereby the work will be firmly held adjacent the cutting tools. 6. In an attachment for lathes, a body portion mounted to move upon the lathe, end plates carried by the body portion, housings carried by each of the end plates, means to mount the housings pivotally thereon, means to mount cutting tools in the housings of one end plate, means to mount rollers upon the housings of the other end plate, means to adjust the rollers to contact with the work, annular recesses in the rear faces of the end plates, annular discs carried in the recesses, slots in the discs, openings in the end plates, pins mounted on the housings and extending through the openings and engaging the slots, a pattern track, a second pattern track similar to the first but having the configurations thereof lagging behind the corresponding configurations of the first track, means to move the ring associated with the tool housings by the first track, and means to move the second ring by the second track, whereby the work will be firmly held adjacent the cutting tools. 7. In an attachment for lathes, a body portion mounted to move upon the lathe, end plates carried by the body portion, tool housings, means to mount the housings pivotally upon the outer side of one of the end plates, housings, and means to mount the same pivotally upon the outer side of the other end plate, semi-circular flanges on the housings, semi-circular shouldered plates secured to the face plates and engaging the flanges of the housings, openings in the face plates, annular recesses in the inner faces of the face plates, annular discs carried in the recesses, slots in the discs, pins carried by the housings and extending through the openings to engage the slots, an opening in the side of the body portion, similar pattern tracks one of which is retarded with respect to the other, arms secured to the discs, and means for connecting the arms to the respective tracks to cause the housings to move simultaneously as the attachment moves along the lathe. 8. In an attachment for lathes, a body portion mounted to move upon the lathe, means to move the body portion, a plurality of tool housings, means to mount the housings pivotally upon the attachment, cutting tools carried by the housings, a bracket carried by the body portion, a groove formed in the bracket, a head movable in the groove, a pattern track, means upon the head to engage the track, and means connected to the head for moving the tool housing simultaneously. 9. In an attachment for lathes, a body portion mounted to move upon the lathe, means to move the body portion, a plurality of tool housings, means to mount the housings pivotally upon the attachment, cutting tools carried by the housings, a bracket carried by the body portion, a groove formed in the bracket, a head movable in the groove, a second groove formed in the head, a secondary head movable in the second groove, means to adjust the position of the secondary head in the groove, a pattern track, means upon the head to engage the track, and means connected to the secondary head for moving the tool housings simultaneously. 10. In an attachment for lathes, a body portion mounted to move upon the lathe, means to move the body portion, a plurality of tool housings, means to mount the housings pivotally upon the attachment, cutting tools carried by the housings, a bracket carried by the body portion, a groove formed in the bracket, a head movable in the groove, a second groove formed in the head, a secondary head movable in the second groove, a block 100 slidale longitudinally in the secondary head, an arm pivotally secured to the block, means secured to the block and housings for moving the latter simultaneously, a pattern track, and means mounted upon the head for 105 engaging the pattern track. 11. In an attachment for lathes, a body portion mounted to move upon the lathe, means to move the body portion, a plurality of tool housings, means to mount the housings pivotally upon the attachment, cutting tools carried by the housings, a bracket carried by the body portion, a groove formed in the bracket, a head movable in the groove, a second groove formed in the head, a secondary head movable in the second groove, a block 110 slidale longitudinally in the secondary head, an arm pivotally secured to the block, means secured to the block and housings for moving the latter simultaneously, a screw carried by the first head, threads in the secondary head engaging the screw, means to turn the screw, a pattern track, and means mounted upon the head for engaging the pattern track. 12. In an attachment for lathes, a body portion mounted to move upon the lathe, means to move the body portion, end plates secured to the body portion, a plurality of housings carried by each plate, means car- 120 125

ried by each plate for moving the housings thereof simultaneously, cutting tools carried by the housings of one plate, steadyng means carried by the housings of the other plate, a bracket having two arms carried by the body portion, a groove formed in each arm, heads movable in the grooves, similar pattern tracks mounted upon the lathe, one being retarded with respect to the other,

means upon the heads for engaging the respective tracks, and means connected to the moving means for each set of housings and the respective heads for moving the former by the latter.

This specification signed this 1st day of Dec. A. D. 1926.

JOSEPH L. MATTHEWS. [L. S.]
